UNITED STATES PATENT OFFICE

162,084

SWINGING PANEL DISPLAY

Joseph J. Robinson, Jr., Dover, Ohio, assignor to
Marsh Wall Products, Inc., Dover, Ohio, a cor-
poration of Ohio

Application May 28, 1949, Serial No. 2,937

Term of patent 7 years

(Cl. D80—9)

To all whom it may concern:

Be it known that I, Joseph J. Robinson, Jr., a citizen of the United States, residing at Dover, in the county of Tuscarawas and State of Ohio, have invented a new, original, and ornamental Design for Swinging Panel Display, of which the following is a specification, reference being had to the accompanying drawing, forming part thereof.

Figure 1 is a perspective view of a swinging panel display, showing my new design;

Fig. 2 a perspective view with the panels removed, viewed from above;

Fig. 3 a perspective view with the panels removed, viewed from below; and

Fig. 4 a perspective view of one of the panels.

I claim:

The ornamental design for a swinging panel display, substantially as shown.

JOSEPH J. ROBINSON, JR.
